Primary Examiner — Eric Goodman*Assistant Examiner* — Amy Wierenga(74) *Attorney, Agent, or Firm* — Nixon & Vanderhye, P.C.(57) **CLAIM**

The ornamental design for a copier, as shown and described.

DESCRIPTION

FIG. 1 is a top, right perspective view of a copier in accordance with my new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The broken lines are shown for the purpose of illustrating portions of the article and form no part of the claimed design.

1 Claim, 7 Drawing Sheets(56)
